(57) **CLAIM**

I claim the ornamental design for a splatter-control cover with handle and vent origices for microwave oven, as shown and described.

DESCRIPTION

FIG. 1 is a perspective view of a splatter-control cover with handle and vent orifices for microwave oven showing my new design;

FIG. 2 is a top plan view thereof;

FIG. 3 is a side elevational view thereof;

FIG. 4 is a bottom plan view thereof; and,

FIG. 5 is a perspective view showing the splatter-control cover with handle and vent orifices for microwave oven in use; the broken lines depict environmental structure for illustrative purposes only and form no part of the claimed design.
